SOUNDING TOY

Joseph Reich, Brooklyn, N. Y.

Application May 19, 1939, Serial No. 274,494

4 Claims. (Cl. 46—197)

This invention relates to sounding toys and more particularly to detonating canes.

The objects of the invention are to provide an improved toy of the kind specified enabling the explosive-holding portion thereof to be made of sheet metal; to provide a construction wherein the parts are readily shaped and assembled; to obtain rigidity of assembly and ample reinforcement; to avoid parts or construction susceptible to injury in use; to enable the explosive holding assembly to be completely assembled before application thereof to the cane or the like; to provide for proper support and guidance of the movable member of "hammer"; to avoid likelihood of the "cap" or percussion element falling from place and yet enable the same to be conveniently applied; to secure simplicity of construction and operation; and to obtain other advantages and results as may be brought out in the following description.

Referring to the accompanying drawing in which like numerals of reference indicate similar parts throughout the several views;

Figure 1 is an elevation of a sounding toy embodying my invention;

Figure 2 is a longitudinal sectional view on line 2—2 of Figure 1; and

Figure 3 is a cross-sectional view on line 3—3 of Figure 2.

In the specific embodiment of the invention illustrated in said drawing, the reference numeral 10 indicates in general a cane having a knob 11 or other handle at its upper end for aiding in manipulating the same. At the lower end of the cane is mounted the assembly 12 for receiving and exploding a cap 13 or other percussion element.

Said assembly is preferably a housing or holding structure fixed to the lower end of the cane and carrying a movable member or hammer irremovably and operatively therein. The housing comprises an outer member or shell 14 shaped from sheet metal, as by drawing, so as to provide an upwardly extending sleeve or ferrule 15 at the lower end of which the metal flares laterally forming a transverse shoulder portion 16 from the outer periphery of which the metal then bends into a longitudinal direction again to form side walls or apron portion 17 of the housing.

Within, and as the upper wall of the housing is provided a disc 18, also preferably of sheet metal of substantially a diameter enabling it to fit within the apron portion 17 and flatwise against the under side of shoulder 16. This disc

18 is held upwardly in place against the shoulder by engagement at its underside and next its edge of the upper edge of an inner cylindrical wall 19 fitting nicely against the inside of apron portion 17. This wall 19 is also preferably sheet metal, and as shown, bends inwardly at the bottom part to form a transverse bottom wall 20 with a central neck 21 depending therefrom for receiving and guiding the shank 22 of hammer 23. The lower edge or margin of the outer wall 10 or apron 17 is spun or otherwise crimped or bent in to underlie the outer margin of bottom wall 20 of the inner member, thereby assembling the inner and outer members and the disc in firm relationship to each other. The double thickness 15 of the circumferential wall thus obtained for the assembly gives the desired strength where most needed in resisting damage resultant from striking the cane on the ground.

The apron portion 17 of the outer member is 20 cut away for a part of its circumference to provide an opening 24 for insertion of the cap 13. Similarly, the inner member is cut away for a part of the periphery of its wall 19 to cooperate with the cut away portion of the outer wall for 25 making the desired opening to the interior chamber of the assembly. It will be observed that the two cut away portions mentioned each extend to the ends of the respective members in which the cuts are made, but that the retained cylindrical 30 portion of the outer member above the cut forms the upper edge of the completed opening and the retained cylindrical portion of the inner member below the cut forms the lower edge of the completed opening. These mentioned retained cylindrical portions above and below the cut away portions accordingly form ledges for retaining the cap from inadvertent dislodgement. Furthermore, the side edges of the opening in the outer member preferably curl in somewhat to prevent rotation of the inner member 35 with respect to the outer member.

The movable member or hammer 23 preferably provides a flat head 25 from which centrally depends shank 22 heretofore mentioned. The head 45 is positioned within the chamber formed by the fixed assembly above described and the shank is of sufficient length to enable it to always protrude below the neck 21 even when the head is raised to engage top wall or disc 18, as shown by 50 dotted lines in Figure 2.

It will be finally noted that the assembly may be completely manufactured ready for use irrespective of the cane 10, to which it may be applied at any subsequent time and without danger 55

of loss of the movable member or separation of the assembly in the meantime. The cane is inserted in the upwardly open sleeve or ferrule and the ferrule suitably pin-pricked, as at 26, or 5 otherwise caused to firmly engage the cane to complete the toy.

I claim:

1. A sounding toy comprising a detonating cane having a chamber forming sheet metal assembly providing a sheet metal top wall for the chamber, and said assembly providing an outer shell member with a side wall and an inner member with a side wall telescoping within and held in place by the side wall of the shell member thereby providing a bottom wall and a double thickness of side wall with one thickness thereof serving as means for spacing the bottom wall from the top wall.

2. A sounding toy according to claim 1 where-
20 in both thicknesses of the side wall have cut away portions substantially juxtaposed for providing a cap-receiving opening, and one of said thicknesses forming the top edge of the cap-receiving opening and the other thickness forming the lower edge of said cap-receiving opening.

3. A sounding toy comprising a detonating can having a housing, said housing comprising an outer shell member having an upper transverse shoulder therein and a sleeve projecting upwardly from the shoulder, a disc in 5 said shell member resting upwardly against said shoulder and closing the bottom end of the sleeve, an inner member having its upper edge engaging against the margin of the underside of said disc and having its lower part turned in- 10 wardly to form a bottom wall parallel to said disc and spaced therefrom, said shell member having a side wall substantially co-extensive with and surrounding the side wall of the inner member and curled in at its lower edge to retain the inner 15 member seated upwardly against said disc, and a hammer within said housing, said hammer having a shank protruding from the housing.

4. A sounding toy according to claim 3 where-
20 in the turned-in bottom wall of the inner mem- 20 ber provides a centrally disposed downwardly extending sleeve receiving and guiding the said shank of the hammer.
